UNITED STATES PATENT OFFICE.

JOHN T. DRUFVA, OF LONG MEADOW, MASSACHUSETTS, ASSIGNOR, BY MESNE ASSIGNMENTS, TO HENRY HYMANN, OF NEW YORK, N. Y.

BATTERY HAND LAMP.

Application filed April 5, 1922. Serial No. 549,808.

This invention relates to battery hand lamps.

One of the objects of this invention is to provide a battery hand lamp in which the spread of the beam of light may be controlled at will.

Another object of this invention is to provide a battery hand lamp in which the lamp bulb may be relieved from pressure of the battery bearing thereagainst, and in which said lamp may be adjusted to control the spread of the beam of light.

Further objects will appear from the detail description taken in connection with the accompanying drawing, in which:

Figure 1 is a cross sectional view of a battery hand lamp embodying this invention; and

Figure 2 is an enlarged detail of Figure 1. Referring to the accompanying drawing, 1 designates the casing which may be either of metal or of fibre or other suitable material. A metal casing is shown in the drawing and the following description will conform thereto. A casing of any other material may be employed with obvious modifications.

The front end of the casing is formed with a screw thread adapted to engage the threaded end 2 of a ring 3 adapted to support the reflector 4 by the engagement of a flange 5 on the rim of the reflector with the upper rim of the ring 3. The upper portion of the ring 3 is threaded to receive a ring 6 adapted to retain a lens or other transparent closure 7 in position covering the reflector. The ring 6 binds the closure 7 against the rim of the reflector 4 so as to secure these parts in place.

Mounted within the forward end of the casing and resting against a shoulder 8 thereon is a metal ring 9 having an inwardly directed flange 10 adapted to support an insulating sleeve 11. Mounted in the insulating sleeve 11 is a tubular guide 12 having an inwardly directed flange 13 at its lower end and being formed at its upper end to provide an inwardly directed flange 14 and an outwardly directed flange 15, the flange 15 resting upon the upper rim of the sleeve 11 so as to position the guide 12 in the casing.

Mounted to slide within the guide 12 is a lamp base, support or holder 16 having an upturned flange or rim 17 adapted to engage the inner surface of the guide 12 for sliding movement therein. The base 16 also has mounted thereon a nipple 18 into which the

lamp bulb 19 may be screwed. Also mounted on the base 16 is a downwardly extending tube 20 having at its lower end an insulating ring 21 supporting a metallic abutment 22 adapted to engage the battery terminal. The abutment 22 is provided with an upwardly extending tubular portion 23 having an in-turned flange 24 and confining an inverted cup-shaped terminal 25 having an outturned flange 26 adapted to engage the flange 24 to limit the upward movement of the terminal. The spring 27 is confined between the terminal 25 and the abutment 22 so as to urge the terminal 25 upwardly to make contact with the center contact of the lamp 19. There is thus established a yielding electrical connection between the battery and the lamp through the abutment 22, the spring 27 and the terminal 25.

Mounted in the upper end of the guide 12 and retained therein by the flange 14 is a metallic ring 28 adapted to receive the upper end of a coil-spring 29, the lower end of which bears against the lamp base 16 to urge the same in a downward direction along the casing. An insulating washer 30 rests on the upper side of the flange 15 and bears against an in-turned shoulder 31 on the ring 3 so that when the ring 3 is screwed into place after the sleeve 11 with its guide 12 and assembled parts have been inserted, the shoulder 31 will retain these parts in place. The guide 12 and, therefore, the lamp base 16 are insulated from all casing parts by the sleeve 11 and the washer 30. A conductor or connecting strip 32 passes between the sleeve 11 and the guide 12 so as to make contact with said guide and connect the same with one terminal of a switch 33 mounted on the casing in the usual manner.

The lower or rear end of the casing is provided with an end cap 34 screwed on in the usual manner. Mounted within this end cap is a cup 35 adapted to receive a bunter or abutment 36. The bunter 36 has a bearing at the bottom of the cup 35 so as to provide a rigid abutment against which the battery 37 may rest. The bunter 36 further provides with the cup 35 an enclosed space 30 forming a casing within which a lamp receptacle 39 may be mounted to receive an extra lamp 40.

In the completely assembled hand lamp, the battery 37 rests upon the bunter 36 and the abutment 22 bears against the upper terminal thereof under the pressure of the spring 29,

the lamp base 16 adjusting itself to the position of the battery by sliding along the guide 12 against the tension of the spring 29. The reflector 4 is open at its lower end to provide 5 a passage therethrough for the lamp 19 and the nipple 18. It will be evident that by adjusting the position of the battery 37 and by screwing up or down on the end cap 34, the lamp base 16 may be moved up or down in the 10 guide 12 and against the tension of the spring 29 and thereby the relative position of the lamp 19 with respect to the reflector 4 may be varied and adjusted. As the reflector 4 is usually of parabolic or other shape capable 15 of focusing a beam of light, this variation in the position of the lamp will result in a variation of the spread of the beam of light thrown forward by the reflector 4.

It is obvious that various changes may be 20 made in details of construction without departing from the spirit of this invention; it is, therefore, to be understood that this invention is not to be limited to the specific details shown and described.

Having thus described the invention, what 25 is claimed is:

1. In a battery hand lamp having a casing and a battery therein, a reflector at one end of the casing, the casing having a guide therein extending circumferentially therearound, a lamp base having a part engaging said guide for movement therealong, and means for moving said base relatively to said reflector.

2. In a battery hand lamp having a casing and a battery therein, a reflector at one end of the casing, the casing having a guide therein extending circumferentially therearound, a lamp base having a part engaging said guide for movement therealong, a spring cooperating 30 with said base, and means for moving said base against the tension of said spring.

3. A battery hand lamp comprising, a metallic battery receiving casing, an insu-

lated guide fitting the lamp end of said casing, a support mounted to slide in said guide, 45 a spring in said guide and engaging said support, a lamp in said support, and means for moving said support along said guide.

4. A battery hand lamp comprising, a metallic battery receiving casing, an insulated guide fitting the lamp end of said casing, a support having a rim mounted to slide 50 in said guide, and a lamp in said support.

5. A battery hand lamp comprising, a battery receiving casing, an insulating sleeve fitting the lamp end of said casing, a support guided to slide within said sleeve, a connecting strip between said sleeve and said support and in electrical connection with the latter to connect the same in the lamp circuit, and a 55 lamp in said support.

6. A battery hand lamp comprising, a metallic battery receiving casing, an insulating sleeve fitting the lamp end of said casing, a support guided to slide within said sleeve, 60 a lamp in said support, and a thrust receiving device on said support adapted to contact with said lamp and the battery.

7. In a battery hand lamp having a casing and a battery therein, a reflector at one end of the casing, a supporting ring for said reflector, a guide in the casing and retained by 70 said ring, a lamp base in said guide and movable therealong, and means for moving said base and said reflector relatively.

8. In a battery hand lamp having a casing and a battery therein, a reflector at one end of the casing, a guide in the casing and adjacent 75 said reflector, a lamp base in said guide and movable therealong, means for insulating said guide from the casing, and means operable from outside the casing for moving said base relatively to said reflector.

In testimony whereof I affix my signature this 21 day of Feb., 1922.

JOHN T. DRUFVA.
